YARN FLUID TREATMENT APPARATUS

Carl E. Hallden, Jr., Avondale, Pa., assignor to E. I. du Pont de Nemours and Company, Wilmington, Del., a corporation of Delaware

Filed Nov. 1, 1961, Ser. No. 149,268

3 Claims. (Cl. 28—1)

This invention relates to an apparatus to be used in treating a bundle of filaments such as a yarn to produce a bulky strand composed of a plurality of individually convoluted filaments, and is more particularly concerned with jets for producing bulky yarn by fluid treatment.

Artificial fibers are normally produced most easily as continuous filaments. Their extreme uniformity and lack of discontinuity makes conventional textile filament yarns much more dense than yarns made from staple fibers. The production of yarns from staple fibers, however, is time-consuming and requires a complex series of operations. The occluded air spaces in staple fiber yarns gives them a lightness, covering power, and warmth-giving bulk not normally possible with continuous filament yarns. Bulky yarns enhance the fullness of woven and knit fabrics, as well as affect other functional properties of textile materials.

The bulk, covering power, and recoverable elongation of continuous filament yarns have been greatly improved by a variety of mechanical and/or heat-setting processes. A most important new product in this area is textured yarn of the type described in U.S. Patent No. 2,783,609 issued March 5, 1957, to Breen. Its production involves exposing a filamentary material to a rapidly moving turbulent fluid to introduce a multitude of crunodal filament loops at random intervals along the individual filaments. These loops and snarls of entangled loops, together with other convolutions, increase the bulk of continuous filament yarns considerably and result in fabrics of improved cover, bulk, handle, and the like. Another technique is described in Belgian Patent No. 573,230, dated November 22, 1958, to the assignee of the present application, in which yarns are introduced into a plasticizing stream of a compressible fluid under turbulent conditions and the filaments are individually crimped into a curvilinear three-dimensional configuration. The effectiveness of these new bulking processes depends upon special apparatus for achieving the desired treatment with turbulent fluid. A new apparatus or jet has now been discovered for utilizing the above turbulent fluid techniques more effectively and to produce improved yarn products with highly useful properties.

An object of this invention is to provide a new fluid jet apparatus for producing bulky yarns of the type and in accordance with the general process disclosed in U.S. Patent No. 2,783,609 to Breen. Another object is to provide an apparatus which is more effective for bulking heavy denier yarns than apparatus previously devised for the fluid jet technique of the Breen patent. Still another object is to provide a new fluid jet for treating yarn which eliminates the need for manual adjustment of the jet by the operator during the texturing operation. Other objects will become apparent from the disclosure and claims.

In the drawings, which illustrate preferred embodiments of the invention,

FIGURE 1 is a side elevation of jet apparatus as used for treating yarn,

FIGURE 2 is a front elevation of the jet, the left side corresponding to the elevation of FIGURE 1,

FIGURE 3 is a side elevation view of the jet embodiment shown in FIGURE 2, and

FIGURE 4 is a view corresponding to that of FIGURE 2 of a modified form of jet.

2

FIGURE 1 illustrates a typical arrangement of apparatus of this invention for treating yarn. Yarn 11 to be treated is fed at a controlled rate, determined by feed rolls 12 and 13, through an appropriate guide 14 and into the jet 15. Air for treating the yarn is supplied to the jet through duct 16 from a source of compressed air, and leaves the jet with the yarn. The textured yarn 17 produced is withdrawn at right angles to the jet exit air stream and in a direction away from the jet body at a rate controlled by take-up rolls 18 and 19.

As shown in FIGURE 2, the jet is suitably made in two parts, a body member 20 and a front plate 21, which are fastened together in proper orientation with suitable screws 22 or other fasteners.

Referring to FIGURE 3, the body 20 is drilled with a passageway 23 for air or other compressed fluid which is admitted through supply duct 16. The front plate 21 is machined to provide a straight inlet throat 24 for entry of the untreated yarn and a larger texturing chamber 25 for treating the yarn which is preferably rectangular in cross-section at right angles to the principal axis of the chamber. The face of body 20 forms one side of both the inlet throat and the texturing chamber. Throat or passage 24 leads the yarn into the texturing chamber 25, where the yarn is immediately penetrated by the fluid stream entering the chamber from fluid duct 16. The zone of turbulence so created exerts an opening action on the yarn components, so that the filaments are formed into loops and whorls by the action of the fluid.

In operation, air is supplied under a pressure which provides a high velocity through texturing chamber 25. A zone of turbulence is created between the exit of the fluid duct and the inner end of the texturing chamber as the fluid rushes into this zone. Yarn is fed into the zone

of turbulence from the yarn inlet throat 24 where it is agitated violently, whipped about, and exits from the texturing chamber 25 along with the high velocity air. The yarn is removed from the air stream immediately upon issuing from the texturing chamber 25 by withdrawing it in the direction away from the face of the body 20. It is important that the apparatus have dimensions such that the air or other suitable compressible fluid utilized will have a velocity equal to at least $\frac{1}{2}$ sonic velocity and preferably approaches sonic velocity where it first strikes the yarn in the zone of turbulence 25, and that the cross-sectional area of the exit of the texturing chamber be of sufficient size to minimize back pressure in the yarn inlet without substantially decreasing yarn velocity in the zone of turbulence.

The angular relationship of the fluid duct to the texturing chamber is highly important to the operation of the jet. As shown in FIGURE 3, the fluid duct 23 approaches the face of the body 20 at an angle of about 30° , in the general direction of yarn travel, to forward the yarn. Angles in the range of 20° to 45° are suitable for this purpose. As shown in FIGURE 2, the axis of the duct is in a plane which is at right-angles to the body face and is skewed at an angle β with respect to the axis of the yarn passage. This angle must be within critical limits for production of textured yarn of the type referred to in connection with Breen U.S. Patent No. 2,783,609. When the angle β is less than 10° crunodal loops are not produced. For texturizing "Dacron" polyester yarn (polyethylene terephthalate), the angle is preferably about 35° and not less than 20° . Angles up to about 45° are satisfactory.

Angles of less than 10° are useful for crimping yarn with steam or other plasticizing fluid, as described in the referenced Belgian Patent No. 573,230, when the formation of crunodal loops is not desired. The crimping treatment can be carried out with β angles from 0° to 10° . The desired angularity can be provided in various ways,

Angles of less than 10° are useful for crimping yarn with steam or other plasticizing fluid, as described in the referenced Belgian Patent No. 573,230, when the formation of crunodal loops is not desired. The crimping treatment can be carried out with β angles from 0° to 10° . The desired angularity can be provided in various ways,

and an alternative embodiment is illustrated in FIGURE 4, wherein the significance of the numbers is the same as in FIGURES 1, 2 and 3 discussed above.

It has also been found necessary that the terminal portion of the side of the texturing chamber opposite to the fluid entrance be tapered outwardly to provide a yarn and fluid outlet of increasing cross-sectional area. Textured yarn is not produced when the angle α (shown foreshortened in FIGURE 3) is less than 7° . This angle of outward taper is preferably about 10° for texturizing nylon, preferably about 20° for texturizing "Dacron" polyester yarn, and not more than 30° . However, it has again been found that different conditions apply to crimping with steam or other plasticizing fluid; angles of 2° to 7° are suitable and angles up to 45° can be used.

The width of the texturing chamber 25 should be slightly narrower than the fluid inlet opening so that the edges partially overlap the fluid opening as illustrated in FIGURES 2 and 4. The absolute and relative dimensions of the yarn inlet throat 24 and the texturing chamber 25 may be varied fairly widely, depending upon the desired treatment, but the texturing chamber must be the larger one. One advantage of this apparatus is the effectiveness in processing a great variety of yarn counts without necessity of a change in the dimensions. For example, with a yarn inlet tube width of 0.030 inch, yarns varying in denier from about 440 to 2000 or more may be readily processed using a texturing chamber width of 0.067 inch. An optimum dimension depends upon the yarn being processed and the degree of texturing desired. Typical widths for the texturing chamber run from 0.04 inch to 0.08 inch. The width of yarn inlet is preferably considerably smaller and can be varied from 0.02 up to 0.05.

For maximum operability, the cross-sectional area of the texturing chamber should be at least 25% greater than the cross-sectional area of the fluid duct 25. The ratio of these two cross-sectional areas can be varied between 1.25:1 up to 2:1.

This jet can be used to texture and bulk any natural or synthetic filamentary material. Synthetic filamentary yarns including polyamides, e.g., poly(epsilon caproamide), poly(hexamethylene adipamide); cellulose esters; polyesters, e.g., polyethylene terephthalate, poly(hexa-hydro-p-xylene terephthalate); polyethylene, polyvinyls and polyacrylics, e.g., polyacrylonitrile, as well as copolymers thereof, are particularly suitable for producing the uniformly bulked products described herein. While the preferred form of material is continuous filaments, the process and resultant improvements occur with staple yarns as well. Both types of materials can be made into

The over-feed rate of the yarns will depend upon the character of the feed yarn as well as the particular characteristics desired in the product. Overfeeds as high as 120% or higher have been used effectively.

Air is particularly preferred as a treating fluid because of its cheapness and convenience. However, heated air, superheated or saturated steam or any other suitable compressible fluid or vapor may be utilized.

The efficient bulking action of this apparatus apparently results from the manner in which the high velocity fluid acts on the individual yarn filaments as the yarn passes through the zone of turbulence. It appears that the yarn is opened and bulked more effectively due to the action of

the fluid striking the yarn at an oblique angle in the zone of turbulence. Not only are the individual filaments within the yarn bundle separately whipped about and randomly twisted so that they become intimately entangled and interlocked with adjacent filaments but at the same

time are formed into loops and whorls uniformly through the yarn bundle to provide the desired bulking action. Apparently, a fluid vortex is also formed which causes intermingling and interlocking of fibers within the yarn bundle, so that the yarn bundle itself remains cohesive under moderate tension after it is removed from the apparatus.

The interlocking and intermingling of the yarn fibers within the bundle may be the reason this apparatus is particularly suitable for bulking heavy denier polyester yarns. Treatment of such a yarn produces a compact yarn bundle which is coherent and further processable in the same manner as a unitary strand. Previously known fluid-treating apparatuses for bulking yarns are less effective,

particularly for the texturing of heavy denier polyester yarns of low denier per filament. Because of the more efficient bulking and unifying results produced by the apparatus of this invention, the feed yarn may be twisted or untwisted, and the product may be twisted or not, as desired. Where a zero twist yarn is fed to the apparatus, the product is a bulked yarn in which the filaments are intermingled and interlocked with one another besides being uniformly loopy throughout, and there is no need to twist this product for further processing.

The examples of the following table illustrate representative bulking conditions for processing yarn with the apparatus illustrated:

Typical Bulking Conditions

Example	Yarn	Air Pressure, p.s.i.g.	Skew Angle β in FIG. 2, degrees	Chamber Angle α in FIG. 3, degrees	Yarn Windup Speed, y.p.m.	Overfeed, Percent

bulky yarns and fabrics having improved bulk, covering power (opacity), and hand.

This apparatus and process are useful for both multi-filament yarns in textile deniers as well as the heavier carpet and industrial yarn sizes either singly or combined in the form of a heavy tow. Fine count and heavy count staple yarns can be processed both as singles and plied. Cruciform, Y-shaped, delta-shaped, ribbon, and dumbbell and other non-round filamentary cross-sections can be processed at least as well as round filaments and usually contribute still more bulk than is obtained with round filaments. The jet and passages therethrough can be of sufficient size to handle multiple ends of yarn, either in the form of warp sheets, ribbons, or tows.

In this table, the yarn descriptions refer to total denier, number of filaments, and twist for the feed yarn being treated. Polyester refers to polyethylene terephthalate yarns. Nylon refers specifically to polyhexamethylene-adipamide yarn. The extent of the bulking action could be increased or decreased as desired by varying the percent overfeed up or down from the values shown in the table.

Since many different embodiments of the invention may be made without departing from the spirit and scope thereof, it is to be understood that the invention is not limited by the specific illustrations except to the extent defined in the following claims.

I claim:

1. In apparatus for making bulky yarn which comprises jet means for treating yarn with fluid, yarn feeding means for passing yarn continuously through the jet for treatment, and fluid supply means for flowing compressible fluid through the jet at a velocity of at least $\frac{1}{2}$ sonic velocity in contact with the yarn to separate yarn filaments and form them into convolutions; the improved jet means characterized by having a texturing chamber with generally rectangular cross-section at right angles to the principal axis of the chamber (path of yarn travel through the chamber) and with inlet and outlet openings at opposite ends of said axis, said inlet opening having a straight throat of smaller cross-sectional area than the chamber for entry of yarn and one face of the throat in the same plane as one chamber face, and a fluid duct for introducing the treating fluid into the chamber through said chamber face; the axis of the duct being in a plane, which plane is at right angles to said chamber face, the axis of the duct being at an angle to said face of from 20° to 45° in the general direction of yarn travel and being skewed at an angle of up to 45° to the principal axis of the chamber; the side of the chamber opposite to said fluid duct having a terminal portion tapering outwardly

at an angle at 2° to 45° providing an outlet of increasing cross-sectional area.

- 5 2. An apparatus as defined in claim 1 wherein said jet comprises a body member and a front plate fastened on one face of the body, said texturing chamber and said yarn inlet throat being cut into the front plate with the face of the body member forming the one side of each, and said fluid duct being drilled through the body member.
- 10 3. Apparatus as defined in claim 2 wherein said front plate is skewed relative to said duct to provide an angle of from 10° to 45° between the principal axis of the texturing chamber and a plane passing through the axis of the fluid duct so as to be at right angles to the face of the body member, and wherein said texturing chamber increases in depth toward the chamber outlet at an angle of 7° to 30° relative to said body face to provide an outward taper.
